UNITED STATES PATENT OFFICE.

BRUNO MARTIN, OF SAGINAW, MICHIGAN.

HOOD OR PROTECTOR FOR GASOLINE TORCHES, ETC.

Application filed June 5, 1925. Serial No. 35,112.

To all whom it may concern:

Be it known that I, BRUNO MARTIN, a citizen of the United States, residing at Saginaw, in the county of Saginaw and

5 State of Michigan, have invented certain new and useful Improvements in Hoods or Protectors for Gasoline Torches, Etc., of which the following is a specification.

This invention relates to certain new improvements in hoods or means to serve as a 10 protector for gasoline torches, fire pots, or analogous devices.

The present invention has for its object, among others, to provide simple and efficient 15 means for protecting not only the long front cast outlet tube, but the whole burner down to and including the drip pan and the main supply tube from the oil reservoir, having for its objects, among others, to serve as a 20 protection against wind and cooling of the main center tube extending from the oil basin.

It has for a further object to provide a 25 hood or protector readily applicable to different styles of torches and burners to protect the burner against wind, rain and snow, and having provision for ready application or removal when desired, as well as quick 30 adjustment so that the cap on the hood may be readily lengthened or shortened according to the style of the burner and then easily affixed in its adjusted position.

Other objects and advantages of the invention will hereinafter appear and the 35 novel features thereof will be particularly pointed out in the appended claims.

The invention in its preferred form, is clearly illustrated in the accompanying drawing, which with the numerals of reference marked thereon, forms a part of this 40 specification; and, in which—

Figure 1 is a side elevation showing my improved protector applied to a gasoline torch or burner.

45 Figure 2 is a substantially central vertical longitudinal section through the hood or protector with the burner shown in side elevation.

Figure 3 is a vertical cross section, as on 50 the line 3—3 of Figure 2, looking in the direction of the arrows.

Figure 4 is an end view of the hood or protector prior to its application to the torch or burner.

55 Like numerals of reference indicate like parts throughout the several views.

Referring to the drawings, 1 designates the burner as a whole, which may be of any well known type, such as a gasoline torch, or other device, of which 2 is the supply tube 60 from the supply reservoir 3, 4 being the drip pan, 5 the valve stem with its actuating handle 6, and 7 the perforated burner, no claim being made in this application to any novelty in the burner or torch per se, the 65 novel feature in the present instance residing in the hood or protector now to be described.

The hood in the present instance comprises the body portion 8, being shown as 70 substantially cylindrical, from opposite sides of one end of which depend the wings or members 9, which are preferably of sufficient height or rather depth to extend below the adjacent portion of the drip pan 4, 75 as seen clearly in Figures 1, 2 and 3. These members 9 may be integral with the body 8, or formed independent thereof and affixed thereto in any well known way.

At the forward end of the member 8 is a 80 cap 10, having a cylindrical portion 11 adapted for sliding engagement with the adjacent portion or end of the member 8, so that the latter may be adjusted longitudinally of said member 8 or removed entirely 85 when desired. At its outer end it is provided with an annular inward extending flange 12, provided with a plurality of openings or perforations 13, shown clearly in Figures 2 and 4. At the other end of the 90 protector oppositely disposed inwardly extending flanges 14 are provided, as seen best in Figure 3, the same being joined to the top portion 15 of the adjacent end of the member 8, as seen clearly in Figures 1, 2 and 3. These flanges 14 are supported by the 95 vertically extended opening or slot 16, as seen in Figures 2, 3 and 4, to fit over the flange stem 5. (Note particularly Figure 3.) Openings 17 may be provided upon the upper face of the portion 15 on the end of the hood or protector, as seen in Figures 1, 2 and 3, for the admission of a restricted quantity of air to aid combustion.

Upon the top of the protector may be mounted a member 18, rising from opposite ends of which are the arms 19 and 20, of any preferred character to support the soldering iron or other implement.

105 On the valve stem 5 is loosely mounted a washer or the like 21, in the present instance shown as dished, while 22 is a larger

washer also shown as dished, and surrounding the stem 5 between said washers is the spring 23. Sleeved upon the stem 5 is the collar or the like 24, provided with a set 5 screw 25 adapted to be engaged with the stem 5 to hold the collar in any desired adjusted position. This provides for lengthening or shortening the device according to the length and type of burner upon which the hood 10 is employed. In applying the hood to the burner the screw 25 is loosened and the hood applied with the member 22 bearing against the adjacent end of the hood or protector, as seen in Figure 2. The end of the hood 15 is brought over the front of the burner, the stem 5 being received in the slot 16 of the flanges 14 of the hood and then the collar 24 is forced against the tension of the spring, the screw 25 is tightened and the hood is 20 held securely in position. To remove the hood the screw is loosened, the collar 24 moved to the right, releasing the tension of the spring against the member 22, when the hood may be readily disengaged.

25 The hood is capable of manufacture at small cost, will be found very efficient and durable in use, not liable to damage in any way, and can be readily replaced by a new one when occasion requires. The hood is 30 preferably made of copper in order to better retain the heat, although other materials may be employed. The hood increases the strong power of the flame and protects the same against wind and water. The hood is 35 perfectly constructed, taking oxygen of the air and carrying the same between the burner and the hood, producing a melting heat. The wind has no chance to extinguish the flame on account of this increased heat between the hood and burner. If the wind 40 enters on one side it will have a chance to go out on the other side.

45 Modifications in detail may be resorted to without departing from the spirit of the invention or sacrificing any of its advantages.

What is claimed as new is:

- 50 1. A protecting hood for gasoline torches, etc., the same embodying a body portion with the depending wings at one end and perforated cap portion at the other end.
2. A protecting hood for gasoline torches, etc., the same embodying a body portion with the depending wings at one end and reticu-

lated cap portion at the other end, said cap portion being adjustably mounted upon the 55 hood body.

3. A protecting hood for gasoline torches, etc., comprising a substantially cylindrical body portion with protecting wings at one end and depending flanges at said end, having 60 an opening for the reception of the valve stem of a burner, and an adjustable cap for said end of the hood.

4. A protecting hood for gasoline torches, etc., comprising a substantially cylindrical 65 body portion with protecting wings at one end and depending flanges at said end, having an opening for the reception of the valve stem of a burner, an adjustable cap for said end of the hood, and resilient means acting 70 upon said cap.

5. A protecting hood for gasoline torches, etc., comprising a substantially cylindrical body portion with protecting wings at one end and depending flanges at said end, having 75 an opening for the reception of the valve stem of a burner, an adjustable cap for said end of the hood, resilient means acting upon said cap, and adjustable means on the stem acting in conjunction with said resilient 80 means.

6. A protecting hood for gasoline torches and the like, comprising a body portion with depending wings at one end and flanges at 85 said end having an opening for the reception of the valve stem, and a closure for said opening.

7. A protecting hood for gasoline torches and the like, comprising a body portion with depending wings at one end and flanges at 90 said end having an opening for the reception of the valve stem, and a closure for said opening, and resilient means acting upon said closure.

8. A protecting hood for gasoline torches 95 and the like, comprising a body portion with depending wings at one end and flanges at said end having an opening for the reception of the valve stem, and a closure for said opening, resilient means acting upon 100 said closure, and adjustable means on the valve stem acting in conjunction with said resilient means.

In testimony whereof I affix my signature.

BRUNO MARTIN.
